UNITED STATES PATENT OFFICE

2,662,222

SEPARABLE PLUG AND SOCKET
CONNECTOR

Salvatore Minneci and Emil J. De Noyers, Pittsfield, Mass., assignors to General Electric Company, a corporation of New York

Application October 31, 1952, Serial No. 318,036

4 Claims. (Cl. 339—255)

1

This invention relates to a separable electrical plug and socket connector of the bayonet type and, more particularly, to improvements in the resiliently expansible socket structure which forms a part of the connector.

Heretofore connectors of the above mentioned type have been provided with resiliently expansible sockets in which there is utilized a "garter spring" arrangement encircling outer contact segments and forcing these segments into clamping engagement about an inner contact element. This garter spring arrangement is subject to several disadvantages. One of these disadvantages is that the garter spring is, in its normal use, subjected to an undesirable tension load. Another disadvantage of the garter spring arrangement is that the garter spring materially increases the size of the connector, thereby resulting in design difficulties in cases where the available space is limited. Still another disadvantage of the garter spring arrangement is that in case the garter spring should fail, the spring would become suddenly detached from the socket structure, thereby resulting in possible damages to surrounding objects or equipment.

In accordance with the present invention, there is provided a novel, simple, and sturdy connector which eliminates the garter type of spring arrangement and its resulting disadvantages. In our novel type of connector, the socket is constructed of a pair of pivoted outer contact segments which are forced about an inner contact element by a "buried" spring arrangement. This buried spring arrangement is constructed and is arranged to cooperate with the connector in such a manner that its incorporation into the connector does not increase the size of the connector, thereby permitting a very compact design. This buried spring arrangement is further characterized by the fact that its springs are not subjected to tension loads but merely act in compression during normal use, thereby resulting in a more durable spring construction. An additional feature of our connector is that the spring is prevented from becoming detached from the connector in case of spring failure.

An object of the invention is to provide a new and improved bayonet type plug and socket connector. Another object of the invention is to provide a compactly designed connector which is provided with a safe and sturdy compression spring arrangement utilizing a minimum of surrounding space.

The invention will be better understood by considering the following description taken in connection with the accompanying drawing, and its scope will be pointed out in the appended claims.

2

In the drawing,

Fig. 1 is a side elevation of a connector embodying the present invention.

Fig. 2 is a bottom view of the connector shown in Fig. 1.

Fig. 3 is a view partly in section taken along the line 3—3 of Fig. 2.

Referring now to the drawing, and more particularly to Fig. 1, there is shown a socket structure generally indicated at 1 and a contact plug structure generally indicated at 2. As shown more clearly in Fig. 3, the socket structure 1 comprises two pivotally mounted outer contact segments 3 which are arranged on opposite sides of a conductor 4. Each of these outer contact segments is provided with a rib 5 which extends laterally across the segment. These ribs, which are semi-circular in cross-sectional shape, form pivots about which the segments rock on opposite sides of member 4. They are forced into contacting relationship with member 4 and the plug structure 2 by buried spring assemblies 6. The contact plug structure 2 is provided with an enlarged generally spherical head 7, and the outer contact segments 3 are provided with opposed recesses which together form a hollow 8 at their outer ends. This hollow 8 is of a generally cylindrical shape and has a flared mouth 8a terminating in a restriction 8b. A hollow of this form will cooperate with the headed plug to permit easy insertion of the plug and will permit the plug to be withdrawn by a force along the plug axis sufficient to overcome the clamping action of the buried spring assemblies 6.

Each buried spring assembly comprises a flanged cylinder 9 disposed intermediate opposite ends of the contact segments. Each of these flanged cylinders forms a mounting for substantially identical spring mechanisms. Each of the

cylinders is fitted into registering openings formed in the conductor 4 and contact segments 3. There is sufficient clearance between each cylinder and its surrounding openings so as to permit a pivotal movement of the contact segments about the pivots 5. Slidably mounted within each flanged cylinder 9 is a headed plunger 10 having a cupped washer 11 held on one of its ends by a cotter pin 12 held in place within an opening in the plunger. Although a cotter pin is shown, it is obvious that any suitable pin might be used instead, especially in view of the fact that the flanged portion of cupped washer 11 is adapted to prevent accidental detachment of such a pin. A compression spring

13 is disposed between the head 14 of the pin and an end wall 15 of the cylinder. This compression spring 13 normally urges the head 14 away from the end wall 15. The spring force on

3

the head 14 is transmitted to the lower contact segment 3 through the washer 11, and the spring force on the end wall 15 is transmitted to the upper contact segment 3 through the cylinder flange 16 which is positioned against the outer surface of this upper contact segment. Thus each spring 13, through its associated mechanism, urges the contact segments 3 together and into contacting relationship with contact plug 2.

It is to be noted that the contact segments 3 are formed with recesses 17 on their outer sides. The flanges 16 and the washer structure 11, 12 fit within the confines of these recesses 17 and do not extend materially beyond the extreme outer surfaces 18 of the contact segments 3. Thus, it may be seen that by utilizing the particular buried spring assemblies 6 shown, a very compact design is provided. This spring arrangement, because of its novel disposition and coaction with its adjacent parts, functions in a very efficient manner and yet does not add to the size of the connector structure.

It is to be further noted that the spring assemblies 6 are spaced and mounted in a line between the pivots 5 and the hollow 8, with that spring assembly 6 adjacent the pivots 5 acting predominantly to force the pivots 5 into firm mechanical and electrical contact with conductor 4, and the other spring assembly 6 acting predominantly to force the contact segments 3 into firm mechanical and electrical contact with the plug 2. The fact that more than one spring assembly is used has the added advantage of preventing any tendency of the contact segments 3 to pivot about a vertical axis through the center of a spring assembly 6. This tendency would exist if only a single spring assembly were present.

It is to be still further noted that in the event of spring failure, the spring 13 would remain housed within its cylinder 9 and would not become detached from the connector.

The operation of the connector is as follows. When it is desired to insert the contact plug 2, it is merely forced into the hollow 8. The pressure of the spherical head 7 against the flared mouth 8a of hollow 8 forces apart the contact segments 3 against the action of the spring assemblies 6. When the spherical head moves past the restriction 8b, the contact segments 3 are forced together by the spring assemblies, and the plug is clamped firmly in place in the position shown in Fig. 3. Similarly, the plug may be withdrawn by exerting an axial force upon it sufficient to force the contact segments 3 apart in opposition to the spring assemblies.

While there has been shown and described a particular embodiment of the invention, it will be obvious to those skilled in the art that changes and modifications may be made without departing from the invention and therefore it is intended by the appended claims to cover all such changes and modifications as fall within the true spirit and scope of the invention.

What we claim as new and desire to secure by Letters Patent of the United States is:

1. In an electrical plug and socket connector of the bayonet type, a socket structure comprising: a rigid conductor having oppositely disposed outer sides; two outer contact segments pivotally mounted on said outer sides, said contact segments being formed with recessed end portions which together form a hollow adapted to receive a contact plug therein; a buried spring assembly connected between said outer contact segments

4

and adapted to force said segments into clamping engagement about a contact plug, said buried spring assembly comprising a flanged cylinder fitted within oppositely disposed registering openings formed in said conductor and said contact segments, the flange on said cylinder being positioned against an outer surface of one of said contact segments, a headed plunger mounted within said cylinder and having an end abutment positioned against an outer surface of the other of said contact segments, and a compression spring mounted between said plunger head and a portion of said flanged cylinder, said spring acting to force said contact segments together so that a contact plug may be clamped in place within said hollow.

2. In an electrical plug and socket connector of the bayonet type, a socket structure comprising a rigid conductor having oppositely disposed outer sides; two outer contact segments, each being pivotally supported upon said conductor by a pivot positioned at one end of the segment, said contact segments being formed at their other ends with recessed portions which together form a hollow adapted to receive a contact plug therein; a pair of buried spring assemblies connected between said outer contact segments and adapted to force said segments into clamping engagement about a contact plug, each buried spring assembly comprising a pair of flanged cylinders, each fitted within oppositely disposed registering openings formed in said conductor and said contact segments, the flange on each of said cylinders being positioned against an outer surface of one of said contact segments, a headed plunger mounted within each of said cylinders and having an end abutment positioned against an outer surface of the other of said contact segments, and a compression spring mounted between each of said plunger heads and a portion of each of said flanged cylinders, said spring acting to force said contact segments together so that a contact plug may be clamped in place within said hollow.

3. The structure set forth in claim 1 further characterized by the outer surfaces of said contact segments being formed with oppositely disposed recessed areas, said recessed areas receiving said cylinder flange and said end abutment; said recesses, said flange, and said end abutment being so constructed and arranged that the flange and the end abutment do not extend materially beyond the extreme outer surfaces of the contact segments.

4. The structure set forth in claim 2 further characterized by said two spring assemblies being spaced and being mounted on a line between the pivots and the hollow; one of said spring assemblies acting predominantly to force the pivots into firm electrical contact with the conductor; and the other of said spring assemblies adapted to act predominantly to force the contact segments into firm electrical contact with a contact plug.
